S. R. Roscoe.

Fire Escape.

N° 12,643.

Patented Apr. 3, 1855.

UNITED STATES PATENT OFFICE.

STEPHEN R. ROSCOE, OF CARLISLE, NEW YORK.

FIRE-ESCAPE LADDER.

Specification of Letters Patent No. 12,643, dated April 3, 1855.

To all whom it may concern:

Be it known that I, STEPHEN R. ROSCOE, of Carlisle, Schoharie county, State of New York, have invented a Portable Ladder for 5 a Fire-Escape or for Any Purpose to which a Ladder can be Applied; and I declare the following specification, with the drawings forming part of the same, to be a full and accurate description thereof.

10 Figure 1 represents in profile a ladder of three sections, with the apparatus for elevating and sustaining it. Fig. 2 exhibits in perspective the lower side of the upper end of one of the sections, showing the rack 15 teeth &c. Fig. 3 exhibits in perspective the upper side of part of two sections, with the lower end of the upper section. Fig. 4 shows a section into the lower end of the 20 upper ladder, with the arrangement of the 25 detent that keep the sections from sliding over and other.

A A A A is a frame work of sufficient height to support the sections of the ladder, and of proper width to allow them to 25 lie between its sides and of length enough to carry the elevating apparatus.

B, C, D are the sections of the ladder, C and D extended and secured to each other by the devices hereinafter described, C being 30 in the progress of extension beyond B and coming up from behind it. When the ladders are down and lie in their places S lies behind B and D behind C, the bottom of each being on the platform P, and the 35 bottom of B being hinged to the platform at H. This platform slides a small distance back and forth to accommodate itself to the movement of the ladders, as they rise and fall; the pressure of the sections behind each 40 other forcing the whole mass to the front, and their rising drawing the platform back again. To move the sections up and down there are a pair of toothed wheels W on one 45 axis one for each side of the ladder, taking into the under side of a rack E attached to each under side of the ladder; the rack being constructed in the manner shown in Fig. 2.

The winch x, ratchet y and pall z for 50 these wheels are shown in Fig. 1.

To keep the sections in their places as they move up and down, besides the wheel W, there is a roller R fixed on the frame below the ladder, and another G placed 55 above the ladder about equi-distant from the roller R and the point where the wheel

W gears in the rack E. The roller G is made to press strongly upon the ladder by means of springs S, which operates upon the boxes in which the axis of the roller 60 revolves.

The apparatus for holding the sections together and securing them in their relative positions when extended is shown in Figs. 2, 3, and 4. The ends of the sections in being fitted to each other are not cut at right angles to their line of length, but at such an angle that when the ladder inclines about 25 degrees from the perpendicular the line of junction of the two ends will be perpendicular. Along the outer side of the ladder an iron plate a, a, is secured whose upper end and lower edge is bent at right angles to its plane as shown at b, b. The angle of the wood lying next this bent edge is rabbeted 70 out into a groove, and is cut away far enough from the iron to allow a bent iron hook to be passed in at the upper end of the iron plate and moved along to its bottom at the foot of the section. A bent hook fitting this 75 groove is attached near the bottom of the upper section at h. The lower end of the upper section has attached to it a projecting dovetail tenon of metal or hard wood t Figs. 3 and 4), and the upper end of the lower 80 section is cut into a corresponding mortise m, (Fig. 2) so fitted to each other that the tenon can slip into the mortise from below, and when the ends of the sections coincide properly, the upper shoulder of the 85 tenon shall rest firmly against the upper end of the mortise. To prevent the upper ladder from slipping down when the ends have been thus brought together, a detent or latch k is fitted into the end of the upper section 90 95 D. This is a bent latch of iron lying in a cavity in, and passing obliquely through the ladder, and pivoted at or near its own center so that it can vibrate slightly, vertically, permitting each end to project a little 100 beyond the surface of the ladder or to sink down even with the same. The latch is kept projecting from the ladder, as shown in Fig. 4, by a small spring operating near its lower extremity. The upper end of the latch 105 which projects beyond the under side of the ladder lies in the line of the teeth of the rack E and between two of them, so that a tooth of the wheel W can press it in, and consequently depress the detent k.

The operation of the machine is as follows—The section ladders lie in a tier, one

behind the other, the lowest section in front and the upper section behind, the upper section being the longest and resting against the wheel W. On turning the wheel, the section D mounts upward, the iron hook h running along the groove under the iron b b, and keeping the ladders together so that when the bottom of section D arrives at the sloping top of C the bottom of D is guided along the top of C until the upper line of the two sections range, and the dovetailed tenon and mortise fit each other, when the detent k which has been kept down by the pressure of the ladder above it, springs out and prevents D from sagging back along C. To lower the ladder, the wheel W is turned backward, and when the points of junction of two sections have passed just below the wheel, a tooth of it depresses the detent, and allows the upper section to slide down under and along the lower one.

The turning of the wheel in the one direction or the other performs the operation described in succession on any number of sections that may be employed in the construction of the ladder.

I have only described the frame work machinery and ladders, as being all that is essential to describe of my invention, but it is to be understood that the frame is to be mounted upon wheels, in any convenient method to make the machine portable.

What I claim as my invention and desire to secure by Letters Patent in the above described sectional ladder for fire-escapes and other purposes, is—

1. The combination and arrangement of the mortise m, tenon t, spring latch h, hook h and the groove in which it traverses the whole being constructed to operate as described for the purposes set forth: 40
2. In combination with above described sectional ladder, I claim the traversing platform P and traversing roller G so constructed and arranged as to allow the sections of the ladder to be operated as set forth.

S. R. ROSCOE.
